UNITED STATES PATENT OFFICE.

GEORGE M. GRAHAM, OF CHICAGO, ILLINOIS, ASSIGNOR, BY MESNE ASSIGNMENTS, TO
SUSPENSION STEEL CONCRETE COMPANY, A CORPORATION OF DELAWARE.

REINFORCED-CONCRETE FLOOR.

974,658.

Specification of Letters Patent. Patented Nov. 1, 1910.

Application filed April 21, 1909. Serial No. 491,347.

To all whom it may concern:

Be it known that I, GEORGE M. GRAHAM, a citizen of the United States of America, and a resident of Chicago, in the county of 5 Cook and State of Illinois, have invented certain new and useful Improvements in Reinforced-Concrete Floors, of which the following is a specification.

This invention relates to that class of reinforced concrete structures described in detail in my prior Letters Patent No. 865,490, dated September 10, 1907, and has for its object to provide a simple and efficient method of forming the floors and other horizontal portions of a reinforced concrete structure and by means of which checking and cracking due to irregular internal strains is prevented, all as will hereinafter more fully appear.

20 In the accompanying drawings:—Figures 1, 2 and 3 are plan views, illustrating the initial, intermediate and final steps of the present method of forming a multiple unit reinforced concrete floor. Figs. 4, 5 and 6 25 are corresponding longitudinal sections of the same.

Similar numerals of reference indicate like parts in the different views.

As represented in the drawings the supporting frame and skeleton wire center for the concrete floor or like horizontal portion of a building or structure will be of the special construction described and claimed in my companion application, Serial Number 491,346, filed April 21, 1909, and will comprise a construction as follows:—

1 represents the vertical posts; 2 the horizontal round border beams; 3 the horizontal round intermediate beams, secured together 40 by suitable coupling pieces to constitute a multiplicity of frame units or panels of a uniform size and varying number in accordance with the horizontal area of the structure.

45 4 are windings of wire arranged in crossed relation as shown, and made continuous the entire length as well as width of the floor in order to encompass the entire series of floor units or panels above referred to. Said 50 windings are effected under ordinary tension and the strands comprising the lower web of the skeleton center formed by such windings will have an initial sag which is taken up and in turn assumed by the strands comprising the upper web of the skeleton cen-

ter, when the concrete mass is applied thereto, in the manner hereinafter described, to form the floor proper.

The present improvement involves a method of applying the concrete mass in a 60 convenient manner, and with which the sag in the strands of the lower web of the skeleton center aforesaid is very effectively taken up and in turn assumed by the strands of the upper web of the skeleton center, and in an 65 even manner which prevents the subsequent checking or seaming of the concrete mass in the complete setting of the same.

To such end the present improvement consists in the following serial steps: First, the 70 application of the concrete mass to the border portions of central units or panels aforesaid; second, with the setting of said border masses, the application of the concrete mass to the central portions of the 75 aforesaid central units or panels; third, the application of the concrete mass to the border portions of the outer units or panels aforesaid; and fourth, with the setting of said border masses, the application of the 80 concrete mass to the central portions of the aforesaid outer units or panels, to complete the floor formation. With such method of application a uniform dish is attained in the portions of the windings of wire individual 85 to each unit or panel aforesaid; and in consequence a maximum and uniform strength throughout is attained, and with an avoidance of the tendency to checking and seaming usual in large surfaces of concrete when 90 formed as a whole.

With the completion of the floor as above set forth, a mass of concrete is applied to the under web of the skeleton center in any usual and suitable manner. 95

Having thus fully described my said invention what I claim as new and desire to secure by Letters Patent, is:—

1. The hereinafter described method of forming reinforced concrete floors in which 100 the reinforce is formed by wires woven around a multiple unit frame of round tubing, such method comprising the application of the floor forming concrete mass to the border portions of the central units, the application of the mass to the central portions of said central units, the application of the mass to the border portions of the outer units, and the application of the mass to the central portions of border units, such 105 110

applications being successive and following the setting of the preceding application, substantially as set forth.

2. The herein described method of forming reinforced concrete floors in which the reinforce is formed by wires wound in crossed relation around a multiple unit frame of round tubing, such method comprising the application of the floor forming concrete mass to the border portions of the central units, the application of the mass to the central portions of said central units, the

application of the mass to the border portions of the outer units, and the application of the mass to the central portions of border units, such applications being successive and following the setting of the preceding application, substantially as set forth. 15

Signed at Chicago, Illinois, this 12th day of April 1909.

GEORGE M. GRAHAM.
